TAPE APPLICATOR WITH CUTTER SNAP RELEASE

Clarence W. Vogt, Norwalk, Conn.
Application May 6, 1953, Serial No. 353,339
11 Claims. (Cl. 216—21)

This invention relates to devices for dispensing and applying adhesive tapes and embodies, more specifically, an improved apparatus by means of which the tape may be severed effectively at such locations as may be desired after portions of the tape have been applied to desired surfaces.

More particularly, the invention relates to tape applying mechanisms wherein means is provided not only to facilitate the effective application of tape to a desired surface, but also to cut the tape in order that the material applied to the desired surface may be severed from the material remaining on the roll carried by the tape applying mechanism.

In accordance with the above, an object of this invention is to provide, in combination with means for applying tape from a roll to a desired surface, means to facilitate cutting of the tape at any desired location.

Yet another object of the invention is to provide cutting means which accomplishes the desired cutting operation without marring or scuffing the surface upon which the tape has been applied.

In order to accomplish the above and other objects, this invention is embodied in a device having a pressure tongue by means of which adhesive tape may be applied under pressure to a desired surface and wherein the tongue is provided with a cutting edge and control mechanism therefor so that actuation of the cutting edge may be restrained until the device has been moved to such position that the cutting edge is prevented from coming in contact with the surface upon which the tape has been applied.

Other and further objects of the invention will be apparent as it is described in connection with the accompanying drawings, wherein.

Figure 1 is a view in longitudinal section taken in a plane intermediate the sides of the device and showing the position of the parts thereof when the device is in a position of repose;

Figure 2 is a partial view similar to Figure 1, showing the position of the device as it is applying tape to a desired surface;

Figure 3 is a partial view similar to Figure 1, showing the position of the device as it is severing the applied tape from the tape material remaining on the roll;

Figure 4 is a partial view in section, taken on line 4—4 of Figure 1, and looking in the direction of the arrows, this view illustrating the mechanism for controlling the cutting operation;

Figure 5 is a detail view in section showing a portion of one of the side walls of the device;

Figure 6 is a detail view in side elevation showing the pressure tongue and tape cutting mechanism of the present invention; and

Figure 7 is a partial plan view showing a plurality of

2

pressure tongues during the course of one method of manufacturing thereof.

Referring to the above drawings, a tape applying device is illustrated at 10 as being formed with side walls 11 having rear tape roll positioning lugs 12 and 13 which serve to locate the tape roll properly within the holder and with a forward bridge member 14. At the outer end of the bridge member 14, there is provided a reversely extending trigger plate 15 preferably formed out of the material of the bridge member and adapted to release the pressure tongue in a manner presently to be described.

A roll of tape material is shown at 16, the end 17 thereof being shown as stripped from the roll and drawn over a turning bar 18 which is illustrated as being formed on the inner end of a pressure tongue 19 and, if desired, formed in a separate operation from the side walls 11. To facilitate the assembly of the elements, the ends of the bar 18 are formed with projections 20 which are received within mating recesses 21 formed within bosses 22 that are formed out of the material of the side plates 11. When the pressure tongue is assembled, it lies inside and above (as viewed in Figures 1, 2, and 3) snubbing ears 23 that are formed on the lower portions of the side plates 11. An angular snubber portion 24 is formed in the material of the tongue 19 and, outwardly of the snubber 24, the tongue is provided with a pressure member 25 over which the tape slides as it is withdrawn from the roll and applied to the desired surface (as illustrated in Figure 2).

Normally, the snubber 24 presses the tape against the ears 23 to grip and hold (and thus snub) the outer end of the tape 26 against return and escape from the mechanism previously described. The tape is thus held in a position such that it is always ready to be applied to a desired surface.

In order that the means may be provided for cutting the tape without marring the surface upon which the tape is applied, control mechanism is provided for the cutting means as follows. At the outer end of the pressure tongue a serrated cutting blade 27 is secured. The serrated elements of the blade are preferably bent downwardly as shown in Figures 1, 2, and 3, in order that the angle of approach or attack may be such as to insure the entering or piercing of the tape by the points of the cutting blade. To this end an enlarged head 28 may be formed at the outer end of the tongue, the ends of the head being provided with ears 29 having notches 30 formed therein for engaging shoulders 31 that are formed on ears 32 which are preferably formed integral with the forward lower extremities of the side plates 11. To accommodate the elements without interfering with the full width of tape which may be received between the side plates 11, the side plates are preferably formed with outwardly extending bosses 33 upon which the ears 32 are formed.

The device of this invention is preferably made by conventional molding techniques and, to facilitate the assembly of the mating portions of the device, bosses 34 and 35 are provided with interengaging pins and recesses 36 and 37, respectively. The boss 34 is provided with a downwardly extending stop 38, this stop serving to limit the movement of the trigger plate 15 by the engagement therewith of a projection 39 formed on the upper inner surface of the trigger plate.

The operation of the device will be apparent from inspection of Figures 1, 2 and 3. After a roll of adhesive tape has been mounted between the side plates with the outer end thereof snubbed as shown in Figure 1, the tape

may be applied to a desired surface by turning the device counter-clockwise (as illustrated in the drawings) until the pressure surface 25 causes the tape to be applied to the desired surface (Figure 2). In this position the notches 30 engage and latch over the shoulders 31 to hold the pressure tongue in such position where it will remain until it is desired to sever the tape. At this point the natural tendency is to continue to turn the device in a counter-clockwise direction and to press downwardly (in order that the end of the tape may be effectively adhered to the surface upon which it is being applied). The ears 32 are formed of such size and shape that they will require the device to be turned to a point at which downward pressure on the trigger plate 15 will assure the disengagement of the notches 30 from the shoulders 31. The length of the ears 32 thus not only assures that the pressure will be in a proper direction to release the tongue but also assures that the device will have been turned sufficiently to prevent the tongue and cutter from engaging the surface upon which the tape has been applied. As will be seen from Figure 3, this downward pressure causes the trigger plate 15 to engage the ears 29 to dislodge the notches 30 from the shoulders 31 and release the pressure tongue 25. The natural resiliency of the tongue 25 causes it to spring outwardly and thus to cause the serrated cutting edge to pierce and cut the tape.

In the foregoing operation, the angle through which the device is turned (approximately 34°) in accomplishing the cutting operation is indicated at A. Inasmuch as the adhesive side of the tape is exposed to the snubbing ears 23 and is resisting being stripped from the roll, the tape will be maintained relatively taut during the severing operation. Thus tautness is further assured by reason that, just prior to the release of the notches 30 from the shoulders 31, the bowing of the tongue required to effect such release will have caused the snubber 24 to move the adhesive side of the tape into engagement with the snubbing ears 23. It thus will be seen that the pressure that applies the tape to a desired surface causes the adhesive side of the tape to be lifted off of the snubbing ears 23 whereas the pressure that effects the release of the tongue causes the adhesive side of the tape to be pressed against the ears 23.

As will be seen from Figures 6 and 7, the pressure tongue and cutter are preferably formed in multiple in a single molding operation, the cutter being formed of a continuous strip properly located in the mold, and after the molding operation, the strip is severed between adjacent tongues to provide the desired element subsequently to be assembled into the mechanism previously described.

While the invention has been described with specific reference to the accompanying drawings, it is not to be limited save as defined in the appended claims.

I claim:

1. Tape applying and cutting mechanism, comprising a holder adapted to receive a roll of tape, a pressure tongue on the holder and having an outer pressing face to apply tape to a desired surface, means biasing said tongue outwardly with respect to said holder, said tongue being movable inwardly into a tape applying position with its outer face adjacent to the bottom of the holder, a cutting element on the tongue adjacent the outer end thereof, said cutting element being offset inwardly of said outer face, means on said holder and tongue to hold the tongue in said tape applying position, and means on said holder to release the holding means to permit the tongue to move outwardly from its applying position to engage and cut said tape with said cutting element.

2. Tape applying and cutting mechanism, according to claim 1, wherein the tongue holding means comprises a latch means and the releasing means comprises a trigger plate for engaging and releasing the latch means.

3. Tape applying and cutting mechanism, according to claim 1, wherein the tongue holding means comprises

latch means and the releasing means comprises a resilient trigger plate for engaging and releasing the latch means.

4. Tape applying and cutting mechanism, comprising a holder adapted to receive a roll of tape, a pressure tongue on the holder having an outer pressing face to apply tape to a desired surface, a cutting element on and adjacent to the outer end of said tongue, said outer end of said tongue being movable inwardly and outwardly with respect to said holder, a forward bridge member on the holder, a trigger plate on the bridge member, interengaging elements on the tongue and holder to hold the tongue inwardly with respect to said holder in a tape applying position and adapted to be engaged and released by the trigger plate, and means biasing said tongue outwardly with respect to said bridge member to engage said cutting element with and cut said tape.

5. Tape applying and cutting mechanism, comprising a holder adapted to receive a roll of tape, a resilient pressure tongue on the holder to apply tape to a desired surface, said tongue being connected at one end of said holder and having its outer end, normally, biased outwardly from said holder and being, movable inwardly towards said holder to a tape applying position by pressure thereon, a cutting element on the tongue adjacent the outer end thereof, means on said tongue and holder to hold the tongue in said tape applying position, means on said holder to hold the tape taut between the roll and the desired surface, and means to release the holding means to permit the outer end of the tongue to move outwardly from said tape applying position.

6. Tape applying and cutting mechanism, according to claim 1, wherein the cutting element comprises a serrated cutting member, the cutting edge of which lies in a plane at an angle to the outer end of the pressure tongue.

7. Tape applying and cutting mechanism, according to claim 1, wherein the tongue holding means comprises shoulders formed on opposite side walls of the holder, and notches on the sides of the pressure tongue to engage the shoulders.

8. Tape applying and cutting mechanism, according to claim 1, wherein the tongue holding means comprises shoulders formed on opposite side walls of the holder, notches on the sides of the pressure tongue to engage the shoulders, and wherein the releasing means comprises a resilient trigger plate formed integral with the holder.

9. Tape applying and cutting mechanism, according to claim 1, wherein the tongue holding means comprises shoulders formed on opposite side walls of the holder, notches on the sides of the pressure tongue to engage the shoulders, and wherein the releasing means comprises a reversely extending resilient trigger plate formed integral with the holder and having a portion adapted to engage the tape that has been applied to the desired surface.

10. Tape applying and cutting mechanism, according to claim 1, wherein the tongue holding means comprises shoulders formed on opposite side walls of the holder, notches on the sides of the pressure tongue to engage the shoulders, and wherein the releasing means comprises a reversely extending resilient trigger plate formed integral with the holder and having a portion adapted to engage the tape that has been applied to the desired surface, upon rocking of the holder in a direction to remove the pressure plate from the surface upon which the tape is applied.

11. Tape applying and cutting mechanism, comprising a holder adapted to receive a roll of tape, a resilient pressure tongue on the holder to apply tape to a desired surface, a cutting element on the tongue adjacent the outer end thereof, means on said tongue and holder to hold the tongue in a tape applying position, snubbing elements on the holder adapted to be engaged

by the adhesive side of the tape, and releasing means on the holder adjacent to the outer end of said tongue to cause the tongue to move the tape against the snubbing elements and to release the holding means to enable the tongue to move to a position remote from its applying position to engage the cutting element with the tape between said releasing means and said snubbing means and sever the tape and hold the free end thereof by the snubbing elements.
